(57) **CLAIM**

The ornamental design for a mobile terminal short housing, as shown and described.

DESCRIPTION

FIG. 1 is perspective view of the front, bottom, and left side of a mobile terminal short housing showing our new design; FIG. 2 is top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines shown in FIGS. 1-7 are for illustrative purposes only and form no part of the claimed design.
